UNITED STATES PATENT OFFICE

2,488,960

TOY COIN PROJECTING PISTOL

Harold F. Burt, Wilmette, and Adolph Theis,
Aurora, Ill., assignors to Silver-King Corp., a
corporation of Illinois

Application October 27, 1948, Serial No. 56,875

3 Claims. (Cl. 124—27)

1

In certain types of amusement devices a spring-actuated gun is used to shoot coins or similar objects at a target. Since such devices are usually operated without an attendant to supervise their use, they are subject to a considerable amount of abuse. As a result the device must be sturdy, simple, and fool-proof to prevent their being constantly laid up for repairs.

The operator of a place of business frequented by the public may have one or more of the machines in his place of business as an additional source of income. Those persons often are not mechanically inclined, and for a machine to be repaired by them it must be such that, at best, only a rudimentary knowledge of mechanical structures is required.

Furthermore, to obtain the broadest possible market for the devices it is necessary that the manufacturing cost be brought to an absolute minimum. To do this the least number of parts must be used, and each part must be so constructed that the manufacturing process necessary to turn out the part is as simple and as inexpensive as possible.

The principal object of our invention is to devise a gun for an amusement device that will satisfy these requisites. As will hereinafter become apparent, a minimum number of parts are required; the manufacturing tolerances of the parts are not critical; and simple methods of forming the parts may be used. Yet when assembled, the gun is sturdy and is able to withstand a large amount of abuse without any impairment of its simple, positive operation.

A further advantage is the ability of the owner to remove foreign materials from the gun barrel without the necessity of dismantling the gun. For some unexplicable reason, children seem to delight in stuffing paper or other objects into the gun, possibly to see if they can be shot therefrom. Invariably the objects will clog the barrel, and in the past it has been necessary to disassemble the gun and clean it before it can again be placed into operation. We have provided means for cleaning the barrel without resorting to the time-consuming job of removing it from the amusement device and taking the gun apart.

Additional objects and advantages will become apparent from the following description

10

taken in conjunction with the drawings, in which Fig. 1 is a perspective view of an amusement device of the type with which our invention is used;

Fig. 2 is an elevation of the gun with a portion broken away to illustrate the trigger and hammer mechanism; and

Fig. 3 is a perspective view of the sear used in the hammer mechanism.

15

Fig. 1 illustrates an amusement device 10 in which the player shoots a coin from a gun 11 at a target 12. After each time a coin is shot from the gun, plunger 13 may be pulled to release a gum ball into receptacle 14. An opening 16 is provided in the center of target 12, and if the player is able to shoot the coin through opening 16, the coin is returned into receptacle 17. The upper surface of the amusement device is usually covered with a glass or plastic hood (not shown). If desired, the machine may be used for dispensing confections other than gum.

20

The gun is suspended from the front of the machine by means of a pair of trunnions 21 attached to either side of the gun body, which trunnions are suspended in internal openings in a pair of brackets 22 attached to the front face of the amusement device 10. Brackets 22 are held in place by means of bolts projecting through the front face of the amusement device, the heads of the bolts being reached from the inner side of the amusement device.

25

The body of the gun 11 is formed from two castings 23 and 24 which are held together by means of three screws 25. An internal opening 27 is formed within the barrel of the gun during the casting process, the size of the opening being determined by the dimensions of the coin 28 which the gun is to accommodate. At the breach end of the gun an upwardly projecting chute 29 is formed to permit the insertion of the coin, and this chute communicates with barrel opening 27. A hammer 31, having a downwardly projecting arm 32, is pivotally mounted within the gun body by means of a screw 33 projecting through an opening in the lower end of arm 32. In Fig. 2 the hammer is shown in the released position in dotted lines and in the cocked position in full lines.

30

The upward forward portion of the hammer is cut away, as indicated at 34, to provide a shelf

35

on which the coin may be caught when it is dropped into the loading chute, and also to form a striking face for projecting the coin when the hammer is released from the cocked position. A thumb latch 35 is formed into the upper rear portion of the hammer 31 to provide means for cocking the hammer.

A sear 31 is pivotally attached to the hammer by means of a cap screw or rivet 38 passing through opening 39 in the sear and being affixed to hammer 31. The forward end of sear 31 is abruptly reduced in height to form a notch 41 in the lower edge thereof. A stop 42, which is made from a screw threaded into side 24 of the gun body, is adapted to be engaged by notch 41 of the sear 31 to hold the hammer in cocked position. The rearward end of the sear is beveled upwardly, as indicated at 43, coming to a slightly rounded point adjacent the upper edge of the sear. Beveled end 43 projects slightly beyond the rear edge 44 of hammer 31.

A leaf spring 46, held between abutments 47 and 48 cast into side 24 of the pistol, is used for the dual purpose of providing the energy to project coin 28 from the gun and to bias sear 31 against stop 42 so that when the hammer is retracted into the cocked position, the notch 41 in the sear will drop behind stop 42. To achieve this the upper end of spring 46 is positioned to engage the beveled end 43 of the sear slightly above the pivotal axis of the attachment of the sear to the hammer.

The spring pressure is directly exerted against the portion of end 43 of the sear adjacent the upper edge thereof and serves to induce a counter-clockwise rotation of the sear with respect to the hammer. The spring pressure is indirectly communicated to hammer 31 through sear 31 to produce a counter-clockwise rotation of the hammer when it is released from the cocked position. An abutment 51 on the forward edge of arm 32 of the hammer acts as a stop to limit the forward motion of the hammer by contact with an abutment 52 cast into portion 24 of the gun body.

A trigger 53 is pivotally mounted by means of screw 54 threaded into one side of the gun body. The upper portion of the trigger forms a cam 56 to engage the forward end 57 of sear 31. If the trigger is pulled when the hammer is in cocked position, the cam portion 56 of the trigger bears against finger 57 of the sear, pivoting the sear in a clockwise direction about connection 38. The pivotal movement disengages notch 41 from stop 42 to allow the hammer 31 to be abruptly moved forward by spring 46 projecting coin 28 from the gun.

In the past when it was necessary to remove any foreign material from the gun barrel, the owner has been obliged to remove the gun 11 from the amusement device 10 and dismantle the gun to perform the cleaning operation. This normally required removing the rear portion of the amusement device 10 to gain access to the screws holding brackets 22 to the forward face of the device and removing those brackets to allow the gun 11 to be withdrawn. To eliminate the necessity of doing this we have provided a clean-out slot 61 longitudinally along one side of the gun barrel and communicating with opening 27 within the barrel. One end of slot 61 forms an enlarged opening 62. A similar circular opening 63 is formed in side 24 of the gun body opposite the enlarged opening 62 in side 23. Thus if any foreign material should become lodged in the gun barrel, a small tool may be inserted

within slot 61 to move the foreign matter rearwardly into line with opposed openings 62 and 63 through which the foreign material may be removed.

From the foregoing description the simplicity of the construction of the gun will be apparent. The two halves 23 and 24 of the gun body may be formed of castings. The single, simple actuating spring 46 may be clipped from a strip of spring stock. The three moving parts—hammer 31, sear 31, and trigger 53—may be formed by casting or blanking. The only other necessary parts are standard screws or rivets. There is substantially nothing to get out of order or to cause malfunction of the gun, but if, by any chance, that should occur, it would be easy for the most inexperienced novice to dismantle the gun, ascertain what the defect was, and make the necessary correction.

We claim:

1. In a gun of the type for use in an amusement device wherein a coin is shot at a target, the combination of a hollow gun body comprising separable halves, a hammer within the gun body and pivotally secured at its lower end to the body and having a coin-engaging portion adjacent its upper end, a sear loosely pinned to the hammer intermediate said coin-engaging portion and said pivotal connection with the gun body and extending forwardly, said sear having a forwardly facing shoulder adapted to engage a projection on the gun body to hold the hammer in cocked position, a spring for urging the hammer and sear forwardly, and a trigger movably mounted on the gun body and having a sear-engaging surface for disengaging said forwardly facing shoulder on the sear from said body projection whereby the force of the spring propels the hammer forwardly.

2. In a gun of the type for use in an amusement device wherein a coin is shot at a target, the combination of a hollow gun body comprising separable halves, a hammer within the gun body and pivotally secured at its lower end to the body and having a coin-engaging portion adjacent its upper end, a sear loosely pinned to the hammer intermediate said coin-engaging portion and said pivotal connection with the gun body and extending forwardly, said sear having a forwardly facing shoulder adapted to engage a projection on the gun body to hold the hammer in cocked position, a spring for urging the hammer and sear forwardly, and a trigger movably mounted on the gun body and having a sear-engaging surface for disengaging said forwardly facing shoulder on the sear from said body projection whereby the force of the spring propels the hammer forwardly, said spring engaging a rearwardly extending portion of the sear above the center of said pinned connection, whereby the spring also urges the sear about its pivotal connection with the hammer and into firm engagement with said projection on the gun body.

3. In a gun of the type for use in an amusement device wherein a coin is shot at a target, the combination of a hollow gun body comprising separable halves, a hammer within the gun body and pivotally secured at its lower end to the body and having a coin-engaging portion adjacent its upper end, a sear loosely pinned to the hammer intermediate said coin-engaging portion and said pivotal connection with the gun body and extending forwardly, said sear having a forwardly facing shoulder adapted to engage a projection on the gun body to hold the hammer in cocked

position, a spring for urging the hammer and sear forwardly, and a trigger movably mounted on the gun body and having a sear-engaging surface for disengaging said forwardly facing shoulder on the sear from said body projection whereby the force of the spring propels the hammer forwardly, said gun body halves having transverse aligned holes adjacent to the forward position of the hammer, and a forwardly extending slot in one of the halves communicating with the opening in said gun body half.
